(57) **CLAIM**

The ornamental design for a cartridge for cleaning device for shavers, as shown and described.

DESCRIPTION

FIG. 1 is a perspective view showing my design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

The broken line showing of portions of the cartridge for cleaning device for shavers is included for the purpose of illustrating portions of cartridge that form no part of the claimed design.
